(57) **CLAIM**

The ornamental design for a ceiling light, as shown and described.

DESCRIPTION

FIG. 1 is a perspective view of a ceiling light showing our new design,

FIG. 2 is a front elevational view of the ceiling light,

FIG. 3 is a rear elevational view of the ceiling light,

FIG. 4 is a left side elevational view of the ceiling light,

FIG. 5 is a right side elevational view of the ceiling light,

FIG. 6 is a top plan view of the ceiling light; and,

FIG. 7 is a bottom plan view of the ceiling light.

The broken lines in the drawings illustrate portions of the ceiling light and form no part of the claimed design.
